CLAIM

The ornamental design for a palm held hair clipper, as shown and described.

DESCRIPTION

FIG. 1 is a left side view showing the new design.

FIG. 2 is a right side view thereof.

FIG. 3 is a top view thereof.

FIG. 4 is a bottom view thereof.

FIG. 5 is a front view thereof; and,

FIG. 6 is a rear view thereof.

The portions of the drawings shown in dotted lines do not form a part of the claimed design.
